PROCESS OF MAKING CHEMICAL PULP AND APPARATUS THEREFOR

Gustaf L. M. Hellstrom, Montreal, Quebec,
CanadaApplication September 2, 1932, Serial No. 631,535
In Canada November 4, 1931

4 Claims. (Cl. 92—7)

This invention relates to paper making and more particularly to the process of manufacturing chemical pulp and the apparatus therefor.

In the preparation of chemical pulp the raw material, if wood, is first reduced to the form of small chips, or if of another kind, to pieces of a like size. Large vertical digesters with conical ends are employed and into these the chips are fed. Chemical liquor is then added and heat is supplied to carry out the cooking process.

The object of this invention is to provide improvements in this cooking process whereby a more uniform and thorough treatment of raw material is obtained, with the result that a higher and more uniform quality of the product is secured, the time required for the process is shortened, and great economy both in the quality of liquor required and the amount of steam employed is gained, and screening losses are reduced to a minimum.

Further objects and advantages will be set forth hereinafter.

Hitherto a large number of patents have been taken out covering a variety of efforts to improve the cooking process. Most of these relate to methods of circulating the liquor contained in the digester. The liquor has usually been drawn out of the digester at one or more points and with or without reheating has been fed back at other points. Screens have been employed to prevent the withdrawal of the material being treated, and the blocking up of these screens by solid matter has been a constant source of trouble. The packing of the material in the lower part of the digester has also been a cause of inefficiency.

By means of this invention, these and other objections to the liquor circulating methods are obviated. It consists briefly in not only withdrawing the liquor but also a portion of the material being treated and returning them again to the digester.

By thus causing a gradual movement and disturbance of the entire charge of the digester, the liquor is able to penetrate the charge uniformly, completely and more rapidly, the heat applied acts throughout the digester at more even temperatures, there is no clogging or packing of the solid portion of the charge, there are no screens or similar obstructions within the digester, to become blocked and seriously affect the cooking process, and the treatment of the entire charge is uniform and complete.

Owing to the recent development of pumps that could handle solids of the nature of wood

chips this method of treatment has become feasible and the continuous disturbance and circulation of the entire charge of a digester can be carried on with facility.

A particularly valuable feature of this invention is that it can be readily applied to digesters now installed with comparatively simple alterations and additions.

The detail application of the method may be carried out in a variety of arrangements without departing from the principles on which it is based, and within the scope of the invention specified.

In the description and specification hereafter, reference will be made to the accompanying drawing in the form of diagrams, in which,

Figure 1 shows a pump operated type.

Figure 2 shows a screw operated type.

Figure 1 shows a digester 1 of the type commonly adopted in the sulphite process at the present time.

This has an inlet 10 at the top through which the chips or material to be treated are admitted. It has the outlet 11 at the bottom leading to the blow valve 12 and blow pipe 13 through which the cooked pulp is removed when the treatment is completed. Connected to the outlet 11 is a second valve 14 and large pipe 15 leading to a pump 2 driven by a motor 20. From the pump 2 a similar large pipe 21 leads upwards to a bend 22 with a valve 23 and second inlet 24 in the upper conical end of the digester 1. Auxiliary steam jets 3 may be provided to the pipe 15, pipe 21 and bend 22. The outlet 11 also has a valved steam feed pipe 30 and there may be steam inlets at the top of the digester but which are not shown. Surrounding the digester may be one or more manifolds 6 with a series of small inlets 60 through the wall of the digester. These manifolds 6 have steam feed pipes 31 whereby a series of steam jets may be forced into the charge of the digester through the inlets 60. There may also be valved connections 25 between the pipe 21 and the manifolds 6. These connections have screened openings into the pipe 21, whereby only fluid can pass into the manifolds 6.

Figure 2 shows a digester 1 of similar type with one or more large pipes 21 with bends opening into the digester adjacent to the inlet 10 and outlet 11 at 24 and 27. Where the pipe enters the lower part of the digester, a motor driven rotating screw 28 operates to draw a portion of the charge into the pipe 21 and force it upwards and back into the digester 1 at the top through inlet 24.

In Figure 1 means are provided whereby steam

may be injected into the mass at suitable points to maintain the proper temperature and assist in the mixing or agitation of the mass. Means are also provided whereby some of the liquor passing upwards may be returned to the digester at lower levels than the main return inlet.

The flow of the material through the pipes may be aided and accelerated by means of steam jets 3 at various points.

10 By means of windows 8 in the pipes 15 and 21 forming inspection points the progress of the cooking can be accurately observed and valuable information obtained as to the effects of varied treatments, in addition to that obtained by the 15 usual control apparatus.

In the types shown in Figures 1 and 2 the pipes 21 may be provided with steam jackets 7 as shown in Fig. 2 whereby the heat of the cooking may be maintained during the passage of the mass from 20 the bottom to the top of the digester.

By means of such construction the charge of the digester consisting of chips and liquor is kept in a state of continuous movement and agitation whereby the liquor is enabled to penetrate 25 the mass uniformly and the heat maintained throughout the digester at the required temperature.

By such treatment the product will be of a high standard of uniform quality and uneven 30 cooking obviated. The rapid penetration of the liquor throughout the mass will expedite its action on the mass and the duration of the cooking will be greatly reduced.

By means of the process there will be a higher 35 yield and a saving in raw material, liquor and steam. Owing to the saving in time occupied in a cooking, the output of a digester will be increased. The cooking will be under more accurate 40 control than has hitherto been possible by the systems now in operation. Inefficient digesters can be readily converted into highly efficient apparatus at small capital outlay.

It is obvious that this circulation of the charge 45 of the digester might be reversed, and that the flow through the pipes be made to run from the upper part of the digester to the lower part.

In the usual practice of filling a digester, the raw material is fed into the top and the cooking liquor is then pumped into the bottom of the 50 digester, this results in the formation of a bridge

of the raw material a short distance above the main outlet. In order to vary and control the height or level at which such a bridge will form, a suitable quantity of liquor is first pumped into the bottom of the digester before it is filled with the raw material. This bridge will provide a screening medium for the cooking liquor and the amount of raw material to be withdrawn with the liquor in the circulation of the charge can be regulated and the necessary disturbance and mixing of the contents can be controlled.

I claim:

1. An apparatus for cooking fibrous material comprising a digester, a conduit arranged externally of the digester for leading chips and cooking liquor from one end of the digester to the other end of the latter pumping means interposed in said conduit for pumping the liquor and chips therethrough, and means in the conduit between one end of the digester and the pump to clear the conduit between the last mentioned end of the digester and the pump and to feed said pump.

2. An apparatus as claimed in claim 1 in which the last mentioned means comprises a pipe for directing a jet of steam into the conduit in the direction of flow of the liquor and chips from the digester toward the pump.

3. An apparatus as claimed in claim 1 in which the last mentioned means comprises a motor- 105 driven rotating screw.

4. An apparatus for cooking fibrous material comprising a digester adapted to contain cooking liquor and wood chips, a conduit arranged externally of the digester and leading from one end of the digester to the other end of the latter, pumping means interposed in the conduit for forcing cooking liquor and chips from the lower end of the digester to the upper end of the digester, means in the conduit between the lower end 110 of the digester and the pumping means for clearing the conduit and feeding the pumping means, and means in the conduit between the pumping means and the upper end of the digester for clearing the conduit between the pumping means and the upper end of the digester and for assisting in feeding the liquor and chips from the pumping means into the digester.
